Des. 218,772
Patented Sept. 22, 1970

218,772

HOLDER FOR BRUSHES OR THE LIKE

Pincus J. Harris, Rye, Port Chester, N.Y., assignor to Empire Brushes, Inc., Port Chester, N.Y., a corporation of New York

Filed Oct. 20, 1969, Ser. No. 19,633

Term of patent 14 years

Int. Cl. D7—99

U.S. Cl. D44—29

FIG. 1

FIG. 2

FIG. 3

FIG. 5

FIG. 4

FIG. 1 is a top plan view of a holder for brushes or the like embodying my new design;

FIG. 2 is a front elevational view thereof;

FIG. 3 is a bottom plan view thereof;

FIG. 4 is an end elevational view thereof;

FIG. 5 is a cross-sectional view taken on line 5—5 of FIG. 2; and

FIG. 6 is a cross-sectional view taken on line 6—6 of FIG. 2.

I claim:

The ornamental design for a holder for brushes or the like, substantially as shown.
